UNITED STATES PATENT OFFICE.

HANNAH LIEN, OF MINNEAPOLIS, MINNESOTA.

LOCK.

1,157,407.

Specification of Letters Patent.

Patented Oct. 19, 1915.

Application filed February 19, 1915. Serial No. 9,379.

To all whom it may concern:

Be it known that I, HANNAH LIEN, a citizen of the United States, residing at Minneapolis, in the county of Hennepin and State 5 of Minnesota, have invented certain new and useful Improvements in Locks, of which the following is a specification, reference being had to the accompanying drawings.

This invention relates to an improved lock 10 and has for its primary object to provide a lock which is especially designed for use in locking together the ends of trunk ropes or other binders.

It is another and more particular object 15 to provide a lock for the above purpose which embodies in its construction, a plurality of movable locking members and means coöperating therewith to retain the same in their effective positions, and improved means for simultaneously releasing 20 all of the locking members.

With the above and other objects in view, the invention consists in the novel features 25 of construction, combination and arrangement of parts as will be hereinafter referred to and more particularly pointed out in the specification and claims.

In the accompanying drawing forming a 30 part of this application, Figure 1 is a horizontal sectional view of the lock, illustrating portions thereof in plan view. Fig. 2 is a transverse sectional view. Fig. 3 is an elevation of the key, and Fig. 4 is an end elevation of the key.

Referring more particularly to the drawing, the numeral 2 designates the casing of 35 the lock which is formed in two sections, 3 and 4, the section 4 constituting what will be hereinafter known as the body of the lock 40 and 3 constituting the cover therefor. The cover 3 and the body 4 are securely fastened together by means of the transverse bolts 5 which extend through the body and cover, as shown in Fig. 3. Extending centrally 45 from the body 4, is a shaft 6, the outer end of which is formed with oppositely disposed flanges 7, adapted to be fitted into corresponding slots 8, formed in the end of the key 9, whereby the key 9 may be readily engaged over the end of the shaft 6, to rotate 50 the same.

Mounted upon the shaft 6 and adapted for rotation therewith, is a disk 10 and disposed between the lower face of the disk and the 55 body of the casing is a washer 11. The cas-

ing 3 is provided in its periphery with spaced openings 12 and extending inwardly from these openings, are the guide ribs 13, the purpose of which will be hereinafter more fully set forth. Movable disposed in 60 these openings 12, are the hasps or keepers 14 which are formed integral with the arcuate members 15. The keepers 14 are provided in one edge thereof with recesses 18 adapted to receive the lugs 19, angularly extending from the outer ends of the pivoted latches 20. These latches 20 are pivotally connected at their inner ends, as shown at 21, to the disk 10 and the lugs 19 are adapted to engage within the recesses 18 in the 70 hasps 14 to retain the hasps in their locked positions.

The latches 20 are normally retained in their operative positions by means of the coil springs 22, one end of each of said coil 75 springs being secured to a post 23, while the other end thereof bears against the rear of the corresponding latch 20. It will be noted that stops 24 are carried by the disk 10 and adapted to limit the swinging movement of 80 the arms 20, so that they will not pass beyond their locking positions, as shown in Fig. 2. In Fig. 2, I have illustrated the hasps 14 and latches 20 in their locked positions and mounted upon the disk 10 are the 85 springs 25, the free ends of which are adapted to engage the inner ends of the hasps 14, whereby to assist in disengaging the hasps from the casing. In order to prevent inward movement of the hasp 14 beyond the 90 locking point, I provide suitable stops 26 which are carried by the disk 10 and adapted to be engaged by the inner ends of the hasps 14. Thus, it will be apparent that the hasps 14 are inserted through the openings 95 12, the beveled faces 27 of the hasps 14 engaging with the beveled faces 28 of the latches 20 to force the latches 19 away from the stops 24 and permit the hasps 14 to pass into the casing where they will engage the 100 stops 26, the latch 20 engaging in the recesses 18 to lock the hasps 14 against any outward movement. When it is desired to release the latches 19 from the hasps 14, the key 9 is inserted through the opening 29 in 105 the cover 3 and engaged over the flanged end of the shaft 6. The disk 10 is then rotated to disengage the latches 19 from the recesses 18 of the hasps 14. It will be noted that by rotating the wheel in the direction of the 110

arrow, indicated in Fig. 2, the stops 24 will press outwardly upon the arms 20 and disengage the latches 19 from the recesses 18.

My improved lock, as herein shown and described, can be quickly and readily applied to a trunk and, at the same time, it will be understood that this lock, may be formed in different sizes so that it can be used on various size trunks. Furthermore, it will be seen that the device can be quickly and readily applied to a trunk and detached therefrom. The trunk lock itself is extremely simple in construction and can be manufactured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims.

Having thus described this invention, what I desire to claim as new and secure by Letters Patent, is:—

1. A locking device comprising a support, a key actuated rotatable member mounted therein, a plurality of latches carried there-

by, a plurality of keepers with which the latches coact, and guides for the keepers mounted on the support, a rotation of the rotatable member in one direction disengaging the latches from the keepers. 35

2. A locking device comprising a casing, a rotatable member therein, spring actuated latches carried thereby, keepers adapted to be inserted into the casing and coact with the latches, guides for the keepers, a stem on the member, a key engageable with the stem for rotating the member and disengaging the latches from the keepers. 40

3. A rope connecting device comprising a casing, a rotatable disk therein, latches pivotally connected to said disk, a plurality of hasps insertible into the casing and adapted to be engaged with the pivoted latches, key actuated means for rotating said disk, and lugs carried by the disk for engagement 50 with the latches whereby upon rotation of the disk, said latches will be disengaged from the hasps, as and for the purpose set forth.

In testimony whereof I hereunto affix my signature in the presence of two witnesses.

HANNAH LIEN.

Witnesses:

JACOB I. WEDELOR,
H. B. JOHNSON.
